ROTARY PUMP OR MOTOR

Elek K. Benedek, Bucyrus, Ohio

Original application March 12, 1935, Serial No. 10,691. Divided and this application September 2, 1938, Serial No. 228,136

4 Claims. (Cl. 103—161)

The invention relates to a variable delivery, radial piston, hydraulic pump or motor of the rotary reactance type and is a division of my copending application, Serial No. 10,691, filed 5 March 12, 1935.

Heretofore, pumps and motors of this character have been provided with T-head pistons operating in chordal grooves in a rotary reactance. Likewise, as described in my copending 10 application, Serial No. 50,671, filed November 20, 1935, pistons having a plurality of rolling pins have been provided for this purpose, the pins being rotatably mounted in the piston head, one pin being solely for radial load and at least 15 two additional pins being for torque transmission. Such pins operate in chordal grooves of the reactance broadly in the same manner as a T-head, both the T-head and the multi-pin and roller type of piston head operating to transmit both radial thrust and torque, from the cylinder barrel to the reactance.

Again, other types of rotary pumps and motors have been provided wherein a single crosspin is rotatably mounted in the head of the piston, 20 this crosspin being in rolling engagement with arcuate grooves which are in the reactance rotor and are concentric with the rotative axis of the reactance rotor.

In the above-described T-head type and multi-pin and roller type of piston, the grooves and piston heads must cooperate not only to reciprocate the pistons radially of the barrel but also to effect, as nearly as possible, synchronous rotation of the cylinder barrel and rotary reactance.

In rotary reactance types of pumps and motors employing T-head pistons or equivalent, synchronous rotation of the barrel and reactance is necessary to effect proper timing between the cylinder ports of the cylinder barrel and the 35 valving ports or bridges of the pintle. In the rotary floating reactance type of pumps or motors employing a single crosspin only in each piston and circular grooves in the rotary reactance for cooperation with the pins, the problem of proper 40 timing is not so acute as there the relation of all parts of the groove to the dead center line of the bridges of the pintle is maintained in all relative positions of the two rotors without synchronization. But even in this latter type of pumps and 45 motors the piston must withstand not only the hydraulic load but also the torque. The crosspins, however, in this latter case, may have to spin around their axes at an enormous speed, due to the floating connection between the rotors.

50 One of the principal objects of the present in-

vention is to provide a rotary radial piston pump or motor of the synchronized type employing a single rotatable crosspin only for each piston in cooperation with a chordal groove in the rotary reactance with means disassociated from the piston, pin and groove for effecting synchronous rotation between the cylinder barrel and the rotary reactance, thereby assuring the proper valving relation between the pintle and cylinders while at the same time making possible the use of 5 a more effective guiding means for the head of the piston by eliminating the spinning of crosspins about their axes and simplifying the design of the pump or motor.

Before referring to the specific embodiment 15 herein shown for purposes of illustration, it should be noted that in a high pressure, high speed pump or motor, both load and torque transmission are of prime importance, if smooth, quiet and efficient operation is to be maintained. 20 Correlatively, the resultant valving cooperation must be maintained at a high degree of accuracy in order to prevent the entrapment of substantially incompressible working fluid used in such pumps and motors. Improper timing between the 25 pintle and cylinder ports often develops destructive knocks, vibrations, and noise, due either to excessive compression or to improper filling of the cylinders with the working fluid. Such 30 knocks and noise evidence poor volumetric efficiency and improper operation due to improper timing. More specifically, it is necessary, in order to eliminate excessive compression and improper filling of the cylinders, to assure that the 35 pistons complete their strokes to their exact ends and at the exact time that the corresponding cylinder ports are at the dead center position of the valving bridges arranged between the valving ports of the valving pintle.

In other words, the pistons in their in and out 40 dead center positions must be synchronized in space and time with the coincidence of the cylinder ports and the respective bridge centers.

It is, therefore, another object of the present 45 invention to provide a structure in which the pistons reach the exact position desired radially at the instant that the associated cylinders are in proper relation to the dead center line of the pintle bridges.

Other objects and advantages will become apparent from the following specification, wherein reference is made to the drawings in which:

Fig. 1 is a horizontal axial sectional view of a 50 rotary pump or motor embodying the principles 55

of the present invention, and is taken on a plane indicated by the line 1—1 in Fig. 2;

Fig. 2 is a vertical sectional view of the pump or motor, and is taken on a plane indicated by the line 2—2 in Fig. 1; and

Fig. 3 is a vertical sectional view of the part of the pump or motor illustrated in Fig. 1, and is taken on a plane indicated either by the line 3—3 or 3a—3a of Fig. 1.

As more fully described in my co-pending application above referred to, the pump or motor comprises generally a casing 1, in which a valve pintle 2 is fixedly mounted. The valve pintle 2 has diametrically opposite, reversible valving ports 3 and 4, respectively, with timing bridges 5 disposed therebetween.

Rotatably mounted in the casing and preferably upon the pintle 2 is a cylinder barrel 6 having a set of cylinders 7 which are spaced from each other circumferentially of the barrel. Each cylinder 7 has a cylinder port 8 arranged for successive cooperation with the ports 3 and 4 upon rotation of the barrel. The barrel has a radial flange portion 9 in which are radial guideways 10 and clearance holes 11. Reciprocably mounted in each cylinder 7 is a piston 12 having an enlarged head 13 which is reciprocable in and guided within the guideways 10 of the barrel flange.

Rotatably mounted in each piston head and preferably on anti-friction bearings is a crosspin 14, each pin 14 extending parallel to the axis of rotation of the barrel. The ends of each pin extend beyond the lateral limits of the head 13 into a position for cooperating with a rotary reactance in a manner to effect reciprocation of the pistons consequent upon rotation of the barrel and eccentrically disposed reactance.

The reactance comprises a pair of rigid generally circular ring members 16 anti-frictionally supported on bearings 17 in an adjustable reactance stator 18. Carried by the members 16 are reactance rings 19, the reactance rings being rigid with the associated members 16. The members 16 with the reactance rings 19 therebetween are secured against axial separation by suitable bolts 20 extending through the clearance holes 11 of the barrel flange, thus forming a rigid, substantially unitary rotary reactance structure, in cooperation with tubular spacers as at 20a.

Each of the reactance rings 19 has a series of chordal grooves 21, one groove being provided in each ring for each piston pin. The ends of each crosspin 14 are received in rolling engagement within opposite grooves 21 of the rings 19.

The reactance stator 18 is mounted in the casing 1 for movement diametrically of the casing along a path which is parallel to the median or dead center plane or line of the diametrically opposite bridges 5, which plane coincides with the line 1—1 in Fig. 2. Thus, by adjustment of the stator 18 to different positions along said path, the reactance rings are positioned with their axis either coincident with or parallel to and offset from the pintle axis at either side of the pintle axis. This adjusts the stroke of the pump or motor in either direction of rotation.

The valve port 3 is connected by suitable pintle ducts 25 with a main port 26, and the pintle ducts 21 connect the port 4 with a main port 28, the main port 28 being arranged opposite to the port 26 diametrically of the pintle.

The barrel 6 is provided at one end with an impeller 30 and is additionally supported at the

impeller end by suitable bearings 31 interposed between the barrel and the casing.

In order to provide synchronous driving relation between the barrel 6 and the rotary reactance, a positive driving coupling is provided. As better 5 illustrated in Fig. 3, this coupling comprises an O-shaped interponent 40 which partially surrounds the barrel near one end and has diametrically opposite, parallel, inner faces 41 which are arranged for engaging complementary outer faces 42 on the adjacent end of the barrel so that the interponent 40 has inner faces 43 which extend at right angles to the faces 41 and are spaced apart from each other a distance permitting the maximum distance of reciprocation 10 that will occur between the interponent and the end of the barrel during operation of the pump or motor at maximum stroke. Likewise the interponent has external, parallel faces 45 which extend at right angles to the surfaces 41.

The members 16 of the rotary reactance are provided with internal faces 46 parallel and complementary to the faces 45 of the interponent 40. The members 16 also have internal faces 47 spaced apart a distance permitting the maximum 25 distance of reciprocation that will occur between the interponent 40 and the reactance members 16. Thus, the interponent positively drivingly connects the barrel and rotary reactance regardless of the eccentricity of the barrel and reactance, 30 one component of the eccentricity being compensated for through the cooperation of the surfaces 41 and 42, and the other component of the eccentricity being compensated for by the co-operation of the surfaces 45 and 46.

In the form illustrated, anti-friction needle roller bearings, such as indicated at 48, are interposed between the complementary, cooperating faces of the interponent and the barrel and of the interponent and the reactance. Accordingly, 40 all torque transmission between the barrel and the reactance is effected through the medium of the interponent, and the pistons, cylinders and crosspins are relieved from all torque transmission and have only to receive or deliver pressure fluid 45 under direct radial thrust.

The operating grooves 21 of the reactance rotor are not only chordal but are at right angle to a radius from the center of the pintle 2 through a dead center position of the bridges 5 when the 50 associated piston 12 is passing its dead center position of reciprocation and these positions of each piston occur when the associated cylinder 7 is at the dead center line of the pintle bridges 5. Further, adjustment of the reactance is exactly along the dead center line of the pintle bridges 5. It is only when these relations are 55 fully satisfied that precise valving or timing relation is provided. Such timing is necessary because working fluid under high speed operation must remain solid, that is, free from foaming, vapor or air occlusions. Otherwise there will be noise and low volumetric efficiency and, obviously, were the oil compressible due to air bubbles and the like, proper timing could not be obtained, and the power development would not be positive, but springing.

The pins 14 can roll freely along the grooves 21 since they are relieved from all torque transmission. Since only one pin is necessary in this 70 structure, the piston head may be narrower fore and aft of the path of rotation and consequently the flange 9 of the barrel 6 with long guideway 10 for the piston heads can be used in conjunction with chordal reactance grooves and rolling pins.

Thus, in the structure, the single crosspin arrangement with piston heads well guided in long radial guideways in the torque flange of the barrel are combined with the advantages afforded by chordal reactance grooves without the binding of the conventional T-head. Further, the precise timing between the pistons and the valve is favorably affected by the synchronous drive between the barrel and the reactance, without burdening the pistons and cylinders with torque transmission between the barrel and reactance.

Ordinarily a chordal or tangential slot could be used only with a T-head piston or a multi-pin piston, and either the T-head or multi-rollers heretofore have been necessary to bring the dead center line of the pintle bridges coincident with the axis of the piston when the piston is in the innermost and outermost position, that is, dead center position. With only one rolling pin and an arcuate slot, this would not occur, and the amount which the piston was off of dead center when passing the dead center line of the bridges would be the error in timing. This valving problem does not exist in the case of circular grooves because the adjustment of the groove as a circle will always permit reasonably good valving conditions but introduces other undesirable factors. With floating or differential rotary reactances, one single crosspin gives perfect timing between 30 pintle and cylinders with a simple circular groove only in the reactance. Such pins may, however, have to spin about their own axes at destructive speeds, to compensate for the differential motion of the reactance with respect to the cylinder barrel. The tangential grooves furnish pure harmonic impulses while the pistons are relieved from the heave torque transmission.

Having thus described my invention, I claim:

1. In a hydraulic pump or motor of the rotary radial piston type including a rotatable barrel having a plurality of circumferentially spaced radial cylinders, valve means therefor, pistons in the cylinders, respectively, a rotatable reactance means for said pistons and adjustable to dispose its rotative axis coincident with or parallel to and offset from the rotative axis of the barrel, said reactance means having chordal grooves opening toward the zone of the pistons, a single crosspin rotatably mounted in each piston, an end portion of each crosspin extending beyond the associated piston transversely of the path of rotation of the pistons, and the extending end portion of the pins being received in associated grooves.

2. In a hydraulic pump or motor of the rotary radial piston type including a rotatable barrel having a plurality of circumferentially spaced radial cylinders, valve means therefor, pistons in the cylinders, respectively, a rotatable reactance means for said pistons and adjustable to dispose its rotative axis coincident with or par-

allel to and offset from the rotative axis of the barrel, said reactance means having chordal grooves opening toward the zone of the pistons, a single crosspin rotatably mounted in each piston, an end portion of each crosspin extending beyond the associated piston transversely of the path of rotation of the pistons, and the extending end portion of the pins being received in associated grooves, and means disassociated from said pistons, pins and grooves and drivingly connecting the barrel and reactance means for synchronous rotation.

3. In a hydraulic pump or motor of the rotary radial piston type including a rotatable barrel having a plurality of circumferentially spaced radial cylinders, valve means therefor, pistons in the cylinders, respectively, a rotatable reactance means for said piston and being adjustable to dispose its rotative axis coincident with or parallel to and offset from the rotative axis of the barrel, said barrel having a radial flange in the zone of the cylinders and radial guideways in said flange, said pistons having heads reciprocable radially of the barrel in said guideways, said reactance means having chordal grooves opening toward the zone of piston heads, crosspins rotatably mounted one only in each piston head, the end portions of each crosspin extending beyond the associated piston head transversely of the path of rotation of the pistons, the extending end portions of the pins being received in associated grooves, respectively, and means in addition to said pistons, pins and grooves, drivingly connecting the barrel and reactance means for synchronous rotation.

4. In a hydraulic pump or motor of the rotary radial piston type including a rotatable barrel having a plurality of circumferentially spaced radial cylinders, valve means for the cylinders, pistons reciprocable in the cylinders, respectively, a rotatable reactance means for said pistons and being adjustable to dispose its rotative axis coincident with or parallel to and offset from the rotative axis of the barrel, said reactance means having walls spaced apart axially from each other, said barrel having a radial flange in the zone of the cylinders and accommodated between said walls, radial guideways in the flange and aligned radially of the barrel with the cylinders, said pistons having portions guided in said guideways, said walls having chordal grooves opening toward the pistons and flange, crosspins rotatably mounted one crosspin only in each piston, the end portions of each crosspin extending beyond the associated piston transversely of the path of travel of the pistons, and the extending end portions of the pins being received in opposite, associated chordal grooves of said walls, respectively, and means in addition to said pistons, pins and grooves, drivingly connecting the barrel and reactance means for synchronous rotation.
